T. F. VEST

SIGNAL

Filed Jan. 15, 1926

Thomas F. VEST, INVENTOR.
By Frank A. Lehman, ATTORNEY.

UNITED STATES PATENT OFFICE.

THOMAS F. VEST, OF BIRMINGHAM, ALABAMA, ASSIGNOR OF ONE-HALF TO TWO VEST SIGN COMPANY, OF BIRMINGHAM, ALABAMA, A CORPORATION OF ALABAMA.

SIGNAL.

Application filed January 15, 1926. Serial No. 81,453.

This invention relates to signals such as are employed on roadways for giving warning to travelers such as motorists or the like, to indicate danger locations, as railway crossings, road intersections and the like.

It is an object of this invention to provide novel means whereby a signal is provided having novel means for displaying the signals and diffusing light in order that the signal may be seen from a great distance.

It is a further object of this invention to produce a signal of the character indicated in which colored light penetrable plates are associated in certain relation to a reflector as to produce a "glow-like" signal of the character indicated.

It is a still further object of the invention to produce a signal of the character indicated which will be comparatively inexpensive to produce and maintain.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a front view in elevation of a signal embodying the invention;

Figure 2 illustrates a side elevation thereof;

Figure 3 illustrates an enlarged detail sectional view on the line 3—3 of Fig. 1; and

Figure 4 illustrates a perspective view of the colored light penetrable plates employed as parts of the signal.

In the present embodiment of the invention, a suitable post 5 is shown, to which a casing 6 is secured, the said casing being intended as a housing for containing a reflector 7, which reflector may be in the nature of polished metal, or it may consist of a broken glass mirror in the usual way, as the inventor does not wish to be limited with respect to the type of reflector employed, nor to the manner in which it is

formed with relation to the housing, since it may be integral therewith or applied to the housing and secured in any appropriate way.

In the present embodiment of the invention, the channel or seat 8 is formed in the margin of the reflector and a gasket 9 is located in the seat. A lens or transparent plate 10 is applied to the gasket and it covers the whole of the reflector to protect the interior thereof from access of the elements or from being fouled by dust or the like. A screen 11 for protecting the lens and the parts at the rear thereof is secured with the lens to the casing or the body by appropriate fastenings such as clips 12, although the inventor does not wish to be limited with respect to the manner of holding the parts assembled.

As shown in the present embodiment of the invention, the reflector has a seat 13 in which a rib 14 is located, and the said rib is provided with a groove 15 in which a colored light penetrable plate 16 is anchored and the inner edge of the plate is shaped to the contour of the inner surface of the reflector. A colored light penetrable plate 17 is also anchored in the rib and the said colored light penetrable plate 17 stands at an angle to the plate 16 and both plates are located at right angles to the lens. It will of course be understood from an inspection of Fig. 3 that in order to accommodate the colored light penetrable plate or plates as assembled in Fig. 4, the rib will be provided with seats or slots forming clearances for the reception of the colored light penetrable plates.

The colored light penetrable plates are translucent, preferably of glass of definite thickness and depth of color and the device possesses the advantage of visibility and effectiveness in daylight as well as night, and is particularly adapted for railway crossings and where construction work of any kind is in progress.

It is seen from an inspection of the drawing that the colored plates are so arranged within the cone that natural light passes through them at all angles and this results in a steady glow within the reflector. From the fact that the plates are arranged at right

angles to the lens or face plate, the light does not vary throughout the area of the lens. Hence, there is no liability of the appearance of shimmering light or of spots in the lighting field.

I claim:

1. In a signal, a housing and means for supporting it, a curved reflector in the housing, a seat in the wall of the reflector, a rib therein having grooves at right angles to each other, colored light penetrable plates having their edges anchored in the rib, and means for holding the colored light pene-

trable plates in assembled relation to the reflector and rib.

15

2. In a signal, a housing and means for supporting it, a curved reflector in the housing, a seat in the wall of the reflector, a rib therein having grooves at right angles to each other, colored light penetrable plates having their edges anchored in the rib, means for holding the said plates in assembled relation to the reflector and rib, and a yieldable contact for the means for holding the said plates.

20

THOMAS F. VEST.

angles to the lens or face plate, the light does not vary throughout the area of the lens. Hence, there is no liability of the appearance of shimmering light or of spots in the lighting field.

I claim:

1. In a signal, a housing and means for supporting it, a curved reflector in the housing, a seat in the wall of the reflector, a rib therein having grooves at right angles to each other, colored light penetrable plates having their edges anchored in the rib, and means for holding the colored light pene-

trable plates in assembled relation to the reflector and rib. 15

2. In a signal, a housing and means for supporting it, a curved reflector in the housing, a seat in the wall of the reflector, a rib therein having grooves at right angles to each other, colored light penetrable plates 20 having their edges anchored in the rib, means for holding the said plates in assembled relation to the reflector and rib, and a yieldable contact for the means for holding the said plates.

THOMAS F. VEST.

CERTIFICATE OF CORRECTION.

Patent No. 1,625,693.

Granted April 19, 1927, to

THOMAS F. VEST.

It is hereby certified that the above numbered patent was erroneously issued to the inventor, said Vest, and Two Vest Sign Company as joint owners of said invention, whereas said Letters Patent should have been issued to Two Vest Sign Company, of Birmingham, Alabama, a corporation of Alabama, as assignee of the entire interest in said invention, as shown by the records of assignments in this office; and that the said Letters Patent should be read with this correction therein that the same may conform to the record of the case in the Patent Office.

Signed and sealed this 17th day of May, A. D. 1927.

Seal.

M. J. Moore,
Acting Commissioner of Patents.
